UNITED STATES PATENT OFFICE.

CHARLES P. MINGST, OF EVANSVILLE, INDIANA.

PRIMING-CUP.

1,308,913.

Specification of Letters Patent.

Patented July 8, 1919.

Application filed July 18, 1918. Serial No. 245,467.

To all whom it may concern:

Be it known that I, CHARLES P. MINGST, a citizen of the United States, residing at Evansville, in the county of Vanderburgh 5 and State of Indiana, have invented certain new and useful Improvements in Priming-Cups, of which the following is a specification.

The object of my invention is to provide 10 an improved priming cup for an internal combustion engine which can be quickly and easily opened and closed and will remain sealed, once it has been closed.

Another object is to provide a priming 15 cup having a cup pin provided with a valve head arranged and constructed in a novel manner, whereby it will automatically close when the engine starts, should it have been inadvertently left open after the priming of 20 the cylinder.

These objects, and others appearing more 25 fully from the following description, are attained by the provision of a priming cup having a slidable and rotatable pin, devoid of screw-threads, and provided with a laterally arranged handle which rides on a horizontally arranged cam on the cup for the purpose of closing, or opening, the cup. When the handle is turned horizontally, its 30 engagement with the cam securely and quickly seals the head of the pin against the outlet of the cup and the valve head is maintained in sealed position until the handle is turned in the opposite direction. If, however, the 35 valve head is inadvertently left open after priming of the cylinder has been effected, the explosion in the cylinder when the engine is started, immediately closes the valve head and it remains sealed during the 40 explosion stroke.

In the accompanying drawings:

Figure 1, is a side elevation, the valve head and handle being shown in closed position by full lines, and in open position by dotted 45 lines;

Fig. 2, a vertical section, the valve head and handle being shown in open position;

Fig. 3, a section on line 3—3, Fig. 2; and

Fig. 4, a view like Fig. 3, showing a modified feed channel.

The cup appears at 1 and has a screw-threaded stem 2 to screw into the cylinder or engine, as usual; there is also a nut 3 integral with the cup.

Extending through the bottom of the cup and the stem 2 is a delivery duct 4 which is flared at its lower end 5 and is smooth throughout its length.

The upper edge of the cup has a generally horizontally disposed cam 6.

The pin 7 is smooth and devoid of screw-threads and is freely slidable and rotatable in the duct 4 in which it is located. The lower end of the pin is provided with a head 8 tapered at 9 to fit the flared end 5 of the duct to effect a tight closing of the latter. The upper end of the pin is provided with a laterally arranged handle 10, which in the present instance is integral therewith, adapted to ride on the cam 6 to seal or open the cup, according to which way the handle is turned.

To allow suitable feed of the gasoline through the duct 4 the pin may be provided with a groove 11 which may be either 75 straight, or curved as shown; or, as shown at 12 in Fig. 4, there may be provided a channel in the wall of the duct; the pin may have a flattened face in lieu of the groove 11.

Having no screw-threaded engagement 80 with the cup, the pin 7 is free to turn and slide in the duct 4 so that the priming cup can be quickly and easily opened or closed. If the pin is inadvertently left open, after priming, the first explosion in the cylinder, 85 automatically closes the head 8 against the flared end 5 of the duct and seals the cup.

The provision of a rigid, laterally arranged handle such as 10, coöperating with a generally horizontally disposed cam, such 90 as 6, insures tight closing of the valve head 8 regardless of wear of said handle, cam and valve head, and the twisting action exerted on the valve head when the handle is turned insures that the valve head will always tightly fit its seat and be securely held when closed.

What I claim is:

A priming cup which is open at its top and is provided with a valve seat, the upper 100

edge of the open-topped cup having a horizontally arranged cam, in combination with a freely vertically slideable and rotatable pin having a valve adapted to engage said seat, said pin being provided with a laterally arranged operating handle resting on the cam

and adapted to close the valve when the handle is turned and rides upwardly on the cam.

In testimony whereof I affix my signature. 10

CHARLES P. MINGST.
